UNITED STATES PATENT OFFICE.

SALVATORE MAZZEO, OF CLEVELAND, OHIO, ASSIGNOR TO THE PRSCO MANUFACTURING COMPANY, OF CLEVELAND, OHIO, A CORPORATION OF OHIO.

LAMP.

1,088,830.

Specification of Letters Patent.

Patented Mar. 3, 1914.

Application filed March 20, 1913. Serial No. 755,628.

To all whom it may concern:

Be it known that I, SALVATORE MAZZEO, a subject of Italy, residing at Cleveland, in the county of Cuyahoga and State of Ohio, have 5 invented certain new and useful Improvements in Lamps, of which the following is a specification.

My invention relates to improvements in lamps, the present embodiment being particularly designed and adapted for use as an automobile head-lamp, the primary object being to provide a generally improved lamp or light of this class, of exceedingly simple and efficient construction, having certain distinct objects and advantages hereinafter described and pointed out.

A further object is to provide a lamp of this class which will prevent theft or the unauthorized removal of the lamp from the 20 supporting bracket arms by the provision of internally arranged and concealed supporting and clamping members or brackets whereby the clamping or attaching device may only be loosened and the lamp removed 25 by access gained to the interior of the lamp body.

A still further object is to eliminate the commonly employed hinged doors or fronts and to provide an interchangeable lamp, or 30 in other words, to provide a lamp which may be mounted either upon the right or left-hand side of the vehicle.

A still further object is to simplify and improve the construction, arrangement, and 35 assemblage of the parts, and particularly to provide a detachably and removably mounted reflector and glass front adapted to be secured and connected to the lamp body by a single clamping and securing 40 member at the rear of the latter, said securing and clamping member being adapted to draw and maintain the parts in proper relative position whereby to prevent rattle or wear by vibrations.

A still further object is to prevent the 45 theft of lamp bulbs or any unauthorized tampering or meddling with the interior of the lamp, by the provision of an improved detachably mounted front secured and 50 locked in its closed position and adapted only to be opened through the medium of the single attaching and clamping device at the rear of the lamp body and the removal

of the removably mounted reflector, as above referred to.

A still further object is to provide an improved support or clamping sleeve and an adjustably mounted socket therein, whereby the lamp bulb or focus of the lamp may be readily altered or adjusted, as desired.

With the above-mentioned and other objects in view, the invention consists in the novel construction, arrangement, and combination of parts, hereinafter described, illustrated in one of its embodiments in the accompanying drawings, and particularly pointed out in the appended claims.

Referring to the drawings, forming a part of this specification, Figure 1, is a central longitudinal sectional view of a lamp constructed in accordance with my invention. Fig. 2, a front view of the same, certain parts being broken away for the purpose of clearer illustration. Fig. 3, a detached perspective view of the clamping and connecting sleeve at the rear of and extending between the reflector and the rear of the lamp body whereby said parts, including the detachably mounted front carried by said reflector, are detachably drawn together and held and maintained in proper relative position. Fig. 4, a sectional view of one of the improved internally arranged supporting and clamping members taken on line 4-4 of Fig. 1. Fig. 5, a perspective view of a portion of the reflector and detachable front, and illustrating the manner of attaching and locking the latter in position.

Similar numerals of reference designate like parts throughout all the figures of the drawings.

The present embodiment of the improved lamp comprises a lamp casing 1, in the present instance, of substantially conical form, terminating at its front in a beaded rim portion 1^a, and provided at its rear, with an opening 1^b, for receiving and containing the clamping and connecting member herein-after described.

The reflector 2, is removably mounted within and connected to the lamp casing 1, by means of a connecting member 3, extending between the rear portions of the reflector 2, and lamp casing 1, said connecting member 3, also forming an improved support or clamping sleeve for containing and adjust-

ing a tubular shaped lamp socket member 4, of suitable construction, one end forming a connection with a removably mounted lamp bulb 5, and filament 6, and the other or rear end being adapted to receive and contain a removably or detachably mounted connector plug 7. The lamp socket member 4, is adapted to be longitudinally moved or adjusted within the connecting member or sleeve 3, for varying the focus of the lamp, by means of a clamping or thumb screw 8, mounted in clamping lugs 3^a, of the connecting or clamping sleeve 3. The connecting or clamping sleeve 3, is secured to the rear portion of the reflector 2, and is preferably further connected and reinforced by means of an annular flange or collar member 9, the latter being suitably secured to the rear portion of the reflector 2, as by welding or brazing, and likewise secured to the connecting or clamping sleeve 3, said connecting sleeve or member 3, having an externally threaded portion 3^b, extending through the opening 1^b, of the lamp casing and provided with an adjusting thumb nut or collar 10, adapted to bear against the rear portion of the lamp casing and draw and clamp the parts in assembled position, as hereinafter more fully explained.

The glass or lens supporting front 11, is removably connected to the rim portion 2^a, of the reflector, as hereinafter described, so that the front 11, is adapted to be placed in position or removed with respect to the lamp casing through the medium of the connecting member 3, and clamping or adjusting nut 10, as hereinbefore described, said lamp front 11, being provided with a rearwardly extending rim portion 11^a, taking over and surrounding the rim portion 1^a, of the lamp casing, and adapted to be drawn into co-acting relation therewith to prevent rattle, and securely maintaining the same in position by drawing up the clamping nut 10, at the rear of the lamp casing, as shown most clearly in Fig. 1, of the drawings.

As a convenient means for detachably connecting the front 11, to the rim portion 2^a, of the reflector, said rim portion 2^a, is provided with a plurality of circumferentially extending slots 12, having enlarged terminal portions 12^a, the latter being adapted to register with and receive screw heads 13^a, of screws 13, carried on the inner side of the rim portion 11^a, of the front 11, and when the front 11, and reflector 2, have thus been brought together by the registration of the terminal portions 12^a, and heads 13^a, one or the other of the parts 11, or 2, may be shifted circumferentially whereby the slots 12, will be brought into engagement with the heads 13^a, as shown most clearly in Figs. 2 and 5, of the drawings. As a means for locking the parts in their shifted or closed position, as just described, a spring actuated or resisted plunger bolt 14, is provided, said plunger

bolt 14, having a head 14^a, and having an annular recess 14^b, the latter being adapted to register with the adjacent slot 12, when the plunger member 14, is depressed, so that when the reflector 2, or supporting front 11, is shifted circumferentially, the annular recess 14, will traverse the slot 12, until the screws 13, are stopped at the opposite terminal portions of the slots 12, after which the plunger bolt or member 14, may be released or allowed to snap into engagement with the enlarged terminal portion 12^b, of the adjacent slot whereby the parts 2 and 11, are locked as against unlocking circumferential movement.

As a means for preventing the theft or unauthorized removal of the lamp from the bracket arms 15, clamping sleeves or members 16, are mounted within the sides of the lamp case, said clamping sleeves or members 16, being provided with internally arranged and concealed clamping or attaching devices 17, said clamping or attaching devices, in the present instance, consisting of clamping or set bolts 17, the bracket arms 15, being preferably provided with annular grooves 15^a, to receive the ends of the clamping bolts 17, as shown.

By the above arrangement it will be seen that the lamp cannot be removed from the bracket arms 15, without first removing the reflector 2, and attached front 11, by loosening and removing the clamping nut 10, at the rear of the lamp casing, and it will likewise be observed that the lamp bulb 5, cannot be taken from the reflector 2, without first taking out the reflector 2, as above described, and then detaching the front 11, from the rim portion of the reflector 2, by the detachment of the same through the attaching devices above described.

While I have shown the present embodiment of the improved lamp provided with an incandescent bulb or light, it is obvious that the improvements may be readily modified for the use of other sources of illumination.

From the foregoing description, taken in connection with the accompanying drawings, the operation and advantages of my invention will be readily understood.

Having thus described one of the embodiments of my invention, what I claim and desire to secure by Letters Patent is,—

1. In an automobile lamp, a lamp casing provided with internally operable bracket arm engaging and releasing members, a door or front and a reflector having internally arranged connections with the latter and detachably mounted within said casing and normally preventing the operation of said members and connections within and secured to the rear of the latter.

2. In an automobile lamp, a lamp casing, a reflector removably mounted therein, a

glass supporting front, and means for connecting said front to said reflector, said connecting members being only operable for releasing the same when said reflector is removed from said casing.

3. In an automobile lamp, the combination with a conical shaped lamp casing, and a reflector mounted therein; of a front, connecting means for connecting said front to said reflector, means for detaching said connecting means when said reflector and front are removed from said casing, and means operable from the rear of said casing for connecting said reflector and clamping said front to said casing.

4. An automobile lamp, comprising a casing open at its front and closed at its rear, a reflector within said casing, a glass supporting front detachably connected to said reflector, means for detaching said front from said reflector when the latter is removed from said casing, and means operable from the rear of said casing for detachably connecting said parts in assembled position.

5. In an automobile lamp, a lamp casing open at its front and closed at its rear, a reflector, a glass supporting front, means for connecting the latter to and detaching the same from said reflector when the latter is disengaged from said lamp casing, a connecting member extending between the rear portions of said reflector and lamp casing, and means for detachably connecting said connecting member to one of said members.

6. A lamp, comprising a casing open at its front and closed at its rear, a reflector mounted therein, a connecting and clamping sleeve connected to said reflector and adjustably and detachably connected to said casing, a lamp socket member mounted in said connecting and clamping sleeve, and a glass supporting front detachably connected to and carried by said reflector.

7. In an automobile lamp, a lamp casing provided with clamping sleeves within the sides thereof, internally arranged clamping members connected to said clamping sleeves,

a reflector mounted within said lamp casing and detachably and adjustably connected at the rear of said casing, and a glass supporting front detachably connected to said reflector, said reflector and front normally preventing the operation of said clamping members.

8. A lamp, comprising a casing, a reflector therein, a connecting member extending between said reflector and the rear portion of said casing, a glass supporting front detachably connected to said reflector and fitting against the front portion of said lamp casing, and means operable at the rear portion of said lamp casing for securing and moving said connecting member, whereby said reflector and supporting front are clamped and maintained in proper position.

9. An automobile lamp, comprising a lamp casing open at its front and closed at its rear, a reflector, a glass supporting front connected to and carried by said reflector and detachable only when the latter is removed, a connecting and clamping sleeve extending between the rear portions of said reflector and lamp casing, means for detachably connecting said sleeve to one of said members, a lamp socket member mounted in said connecting and clamping sleeve, and an incandescent lamp detachably mounted in said lamp socket member.

10. In an automobile lamp, a casing, a reflector therein, a detachable connecting member extending between the rear portions of said reflector and casing, a glass supporting front closing and opening said casing when said reflector is inserted and removed, respectively, and front connecting mechanism carried by said reflector and only operable to detach said front from said reflector when the latter is removed from said casing.

In testimony whereof I have affixed my signature in presence of two witnesses.

SALVATORE MAZZEO.
